UNITED STATES PATENT OFFICE.

WILLIAM LUMLEY, OF CHICAGO, ILLINOIS.

BRACKET FOR INK-WELLS.

SPECIFICATION forming part of Letters Patent No. 427,883, dated May 13, 1890.

Application filed September 2, 1889. Serial No. 322,719. (No model.)

To all whom it may concern:

Be it known that I, WILLIAM LUMLEY, a subject of the Queen of Great Britain, and a resident of Chicago, in the county of Cook 5 and State of Illinois, have invented certain new and useful Improvements in Brackets for Ink-Well, of which the following is a specification.

This invention relates to improvements in 10 brackets for ink-bottles, but is more especially designed as an improvement upon the invention set forth in Letters Patent of the United States No. 397,558, granted me the 12th day of February, A. D. 1889, in which 15 the vertically-adjustable bracket or gibbet-arm was locked at any desired point upon the gibbet-post by friction alone.

The prime object of this invention is to 20 have the gibbet-arm locked upon the gibbet-post at any desired point by clamping as distinguished from a frictional hold or the action of a set-screw, whereby the marring of 25 the gibbet-post is avoided and the arm securely locked in any adjustable position against accidental falling.

Another object is to combine with such a 30 device an ink well and holder of novel construction, whereby not only is the capacity of the well materially increased, but it is firmly secured in the holder against accidental displacement, but readily adjustable therefrom. These objects are attained by 35 the devices illustrated in the accompanying drawings, in which—

Figure 1 represents a side elevation of an 40 ink-well and bracket therefor embodying my invention; Fig. 2, a plan view thereof, showing the gibbet-post in section; Fig. 3, an enlarged vertical section through the ink-wells 45 and holder therefor; Fig. 4, a detail perspective view of the clamp for the gibbet-arm; and Fig. 5, a side elevation of a modification of my invention, showing a rigid and non-extensible gibbet-arm and a single post.

Similar letters of reference indicate the 50 same parts in the several figures of the drawings.

Referring by letter to the accompanying drawings, A indicates the gibbet-post, preferably composed of an upright cylindrical bar, and where it is desirable to have two ink-wells this post may be bent downwardly,

so as to form two upright posts, as illustrated in Fig. 1, on each of which works a gibbet-arm.

The gibbet-arm B is preferably composed of two sections, with a sliding connection therebetween, obtained by sliding each section longitudinally, and having a set-screw C attached to the end of one section and working through the slot in the other section, by means of which the two sections may be locked in any adjusted position, a guide-stud D projecting into the slot in the section to which the set-screw is attached.

On the inner end of the inner section is rigidly secured a clamp E, formed of a single piece of metal on the arc of a circle of substantially the same diameter as that of the gibbet-post, the terminals of each lying parallel, and one at each side of the gibbet-arm, to which it is rigidly secured. The clamp, however, is of greater width than the gibbet-arm, and that portion thereof lying below the plane of the gibbet-arm—that is, the circular 75 portion and one branch of the straight portion—is cut free from the main body of the clamp, forming two eyes F and G, one above the other, the former constituting a guide for the arm upon the post, while the latter 80 serves the purpose of a clamp.

Through the straight portion H of the clamped portion G works a set-screw I, engaging a screw-threaded opening in the main body of the clamp at the opposite side—that is to say, in the straight portion thereof, which 85 is integral with and not separated from the main body of the clamp.

In operation the set-screw I is loosened, the arm adjusted vertically to any desired position upon the gibbet-post by tightening the set-screw I, causing the clamping portion G to bind tightly upon the post, and the arm may be firmly secured in position, and such clamping will not mar the surface of the post, because the clamping-surface composes substantially the entire periphery thereof, and not at a single point in the periphery, as would be the case in the use of a set-screw. The form or manner of securing the gibbet-post to the desk is immaterial, for, instead of being duplex, as illustrated in Fig. 1, it may be a single upright post, as shown in Fig. 5, attached to the desk-top, or, as shown by the

dotted lines in said figure, the post may be bent to the rear at its lower end and secured to the back wall of the desk; nor is it necessary that the gibbet-arm be made in two sections, so as to be extensible or adjustable, as illustrated in Fig. 1, for, so far as the clamping device is concerned, the arm may be of a single piece and rigid, as between the post and the ink-well supported thereby.

10 On account of the comparatively limited size of the ink-well holder, as a result of which the capacity of the ink-wells is somewhat limited, it is desirable to use in connection with such a holder ink wells or bottles of a construction that provides the maximum capacity in the minimum space, and which also serves to reduce the vibration. To this end I provide the holder *a*, pivoted upon the post *b*, projecting upwardly from, or, if desired, 15 depending from, the outer end of the gibbet-arm, having a series of recesses *c* on the under side thereof and contracted perforations *d* at the upper ends of the recesses, extending through the holder, of less diameter than the recesses. In the recesses lie the ink-bottles *e*, having contracted necks *f*, which project upwardly through the perforations *d* flush with the upper surface of the holder *a*, said necks being screw-threaded on their inner peripheries, into which fits a corresponding nozzle or supplemental neck *g*, screw-threaded on the outer periphery thereof and provided with a lateral flange *h* of greater diameter than the opening *d* in the holder, so that when 20 screwed into position the edges of the opening *d* will be clamped between the flange *h* and the body of the bottles, thus serving to firmly retain the bottle in position within the holder, but also permits the ready removal thereof 25 by the unscrewing of the nozzle *h*.

Access to the ink-well is gained through the central perforation *i* in the nozzle *h*, which may be of any suitable diameter, the smaller of course the better, so far as preventing vibration is concerned, but of sufficient size to accommodate the pens ordinarily employed. In this manner the capacity of the ink-bottles is materially increased, their accidental removal or upsetting absolutely prevented, 30 and while firmly secured in position within the holder are readily removable therefrom.

Obviously it would be no departure from the spirit of my invention to have the ink-bottle secured thereto on the outer periphery thereof and the nozzle screw-threaded on the inner periphery, for the result would be the same in either case.

The screw-cap of the ink-bottles may be made of any suitable material—such as metal, glass, gutta-percha, paper, or any other kind of material that will subserve the intended purpose; but it is preferably made of glass, with the screw-thread molded thereon.

Having described my invention, what I claim, and desire to secure by Letters Patent, 60 is—

1. In an ink-well holder, the combination, with the gibbet-post, of the gibbet-arm, the divided clamp secured thereto, one portion of which constitutes a guide and the other a 65 spring-clamp encircling the post, and a set-screw engaging and guiding the spring portion thereof, substantially as described.

2. In an ink-well holder, the combination, with the gibbet-post *A* and gibbet-arm *B*, of the clamp *E*, rigidly secured to said arm and comprising the eyes *F G*, the spring-arm *H*, and set-screw *I*, substantially as and for the purpose described.

3. The combination, with the ink-well holder provided with a socket on the under side thereof and a contracted portion extending from said socket through the holder, of an ink-bottle fitting in said recess, provided with a contracted neck, a nozzle fitting 85 said neck provided with a peripheral flange lying upon the upper surface of the holder, and a screw-thread connection between said nozzle and bottle, substantially as described.

4. The combination, with an ink-well holder provided with an enlarged recess on the under side thereof and a contracted perforation extending from said recess through the holder, of an ink-well fitting in said recess and provided with a contracted neck 95 screw-threaded on the inner periphery thereof, and a screw-threaded nozzle fitting into said neck and provided with a peripheral flange of greater diameter than the perforation in the holder, substantially as described.

5. In an ink-well holder, the combination, with a longitudinally-adjustable gibbet-arm, a fixed gibbet-post, and a clamp secured to said arm adjustable and slideable upon said post, of an ink-well holder provided with a series of recesses on the under side thereof, ink-wells fitting in said recesses, and separable caps for said wells securing the same in position, substantially as described.

WILLIAM LUMLEY.
